UNITED STATES PATENT OFFICE

DAVID L. DAVIS, OF THORNBURY VILLAGE, ILLINOIS, ASSIGNOR TO MICHAEL-GEORGE COMPANY, OF LIBERTYVILLE, ILLINOIS, A CORPORATION OF ILLINOIS

DESIGN FOR A PENCIL

Application filed January 9, 1930. Serial No. 34,068. Term of patent 7 years.

To all whom it may concern:

Be it known that I, DAVID L. DAVIS, a citizen of the United States, residing at Thornbury Village, in the county of Lake and State of Illinois, have invented a new, original, and ornamental Design for Pencils, of which the following is a specification, reference being had to the accompanying drawing forming part thereof.

The figure is a plan view of a pencil showing my new design.

I claim:

The ornamental design for a pencil as shown.
